HAIR CURLER

Victor M. Newman, New York, N. Y., assignor to
Max M. Newman, New York, N. Y.

Application June 4, 1942, Serial No. 445,692

11 Claims. (Cl. 132—33)

My invention relates to hair curlers and more particularly to hair curlers of the type in which a hair pin supported thereby, is applied to a curl of hair formed thereover. It is a continuation-in-part of my application, Serial No. 428,650, filed January 29, 1942.

An object of my invention is to provide a simplified form of hair curler wherein distinct mandrel elements serve to retain initially the tress of hair so that when the hair is curled thereover, one of said mandrel elements may be withdrawn to reduce the effective thickness of the mandrel thereby reducing the internal pressure on the formed curl and permitting the removal of the mandrel.

Another object of my invention is to provide improved manually operated means for effecting the union between the hair pin and the formed curl.

Another object of my invention is to provide more efficient means for retaining the hair pin before and during the time it is applied to the formed curl and to provide simple and effective means for disassociating the hair pin from the curler after the curl of hair has been duly pinned. In this connection said last named means also serve to preserve the hair pin from injury or distortion attendant with its disassociation from the curler.

Other objects of my invention will be apparent from the following description, it being understood that the above general statements of the objects of my invention are intended to describe and not to limit it in any manner.

In the drawing,

Fig. 1 is a top view of a hair curler embodying my new invention.

Fig. 2 is a side view thereof partly in section to illustrate internal construction.

Fig. 3 is a view similar to Fig. 2 and illustrating the application of the hair pin to the formed curl.

Fig. 4 is a similar view illustrating the condition of the curler after completion of the last operation.

Fig. 5 is a rear view of the curler.

Fig. 6 is a cross-section on the line 6—6 of Fig. 2.

Fig. 7 is a cross-section on the line 7—7 of Fig. 4.

Fig. 8 is a view of a conventional hair pin used in the device.

The housing or support 10 and mandrel member 11 may be integral and may be formed of wood, plastic, metal, etc. The housing 10 is provided with a longitudinal groove 12 in which is disposed the wire 13. The wire 13 extends the length of groove 12 and is bent over and secured to the housing 10 at 14.

Telescoped over the wire 13 for sliding longi-

tudinal movement in the groove 12 is the upper mandrel member 15 which, together with the mandrel member 11 constitutes the effective mandrel of the curler. An operating member 16 is connected, as by soldering, to the mandrel member 15 so as to facilitate the manual operation of sliding it over the wire 13. The operating member 16 is button shaped, although it may assume any form, its function being merely to slide the mandrel member 15. Similarly, the housing 10 is easily replaceable by any form of housing serving the same purpose, i. e., a support.

The sliding mandrel member 15 serves also as the hair pin carrying and spreading member and its construction is such as to perform this function with precision and effectiveness. Mandrel member 15 is tubular and a short distance from the front end thereof, an arcuate section is cut off leaving the bottom portion of the front end. This bottom portion is bent over to form a narrow slotted section 15a, as seen in Fig. 6. The hair pin 18 is of the "bobby" pin type of resilient metal wherein the legs normally abut each other. The lower leg 18a thereof is inserted in the narrow slotted section 15a and pressed in as far as it will go. The insertion will be substantially unresisted at first, but as the hair pin is pushed further, the curved portion 18b of the pin resists the straightening effect which the narrow slotted section 15a has upon it. In consequence, the grip of the hair pin on the narrow slotted section 15a of the mandrel member 15 will be firm and a function of its position in relation to the mandrel member 15. It will be further noted that the uncut mandrel member 15 thereupon serves to spread the hair pin (Figs. 2 and 6) so that it is prepared to embrace the formed curl. The cut portion permits the curl to be disposed practically up to the closed end of the hair pin.

40 A collar 19, transversely concave for finger grip purposes, is provided although this collar 19 might well be integral with the housing 10.

My invention is practiced as follows:

The hair pin 18 is inserted in mandrel member 15 until it is gripped very firmly by the slotted portion 15a on its curved section 18b. A tress of hair is then selected and slid into the small space between mandrel members 15 and 11 where it will be retained. The curler is then rotated so as to form a curl of hair around these mandrel members. The operating member 16 is then rearwardly actuated by the fingers thereby retracting the mandrel member 15 and the hair pin 18. The retraction is continued until the hair pin is caused to embrace the curl. Since there is often some resistance encountered during this motion, the firm grip of the narrow slotted section 15a upon the hair pin 18 prevents undesired displacement of the hair pin before it has completed its function. This position is illustrated in Fig. 3.

The retraction of the mandrel member 15 causes it to telescope the stationary wire 13 and brings the hair pin leg 18a and narrow slotted section 15a toward the wire 13. Referring to Fig. 7, the end of the wire 13 is of substantially flattened cross-section so that it nests within the narrow slotted section 15a and permits said section 15a to telescope it. Accordingly, the continued retraction of operating member 16, mandrel member 15, and hair pin 18 brings about contact between leg 18a and wire 13 which by preventing the entry of the hair pin 18 into the housing 10, effects the separation of the hair pin and the mandrel member 15 since the mandrel member 15 enters the housing 10 as shown in Fig. 4. The pressure of the wire 13 upon the leg 18a overcomes the grip of the hair pin within the narrow slotted section 15a and the mandrel member 15 may therefore be completely retracted within the housing, as illustrated in Fig. 4. Distortion of the hair pin due to ejecting pressure is avoided because the pressure takes place within the confined inner area of the mandrel member 15 and the leg 18a has therefore no opportunity to become bent or otherwise distorted.

Due to the complete retraction of the mandrel member 15, the effective thickness of the mandrel is reduced while the grip of the mandrel on the hair tress is released. The curler may therefore be easily removed from within the formed curl.

In actual practice, the retraction of the mandrel member 15, the pinning of the curl, the ejection of the hair pin and the freeing of the device from the curl is a single, simple movement effected by merely actuating the operating member 16 while maintaining an opposing hold on collar 19.

The curler is then ready for the next curl and the process is repeated to form as many curls as desired.

I have shown a preferred embodiment of my invention but it is obvious that numerous changes and omissions may be made without departing from its spirit.

I claim:

1. A hair curler comprising a support, a lower mandrel member, an upper mandrel member slideable in said support, means on said upper mandrel member to retain a hair pin thereon by embracing one leg thereof and stop means for intercepting said leg of the hair pin as said upper mandrel member is slid into said support.

2. A hair curler comprising a support, a lower mandrel member, an upper mandrel member slideable in said support, means on said upper mandrel member to support a hair pin thereon by embracing the lower leg thereof and to spread said hair pin and stop means for intercepting said lower leg as said upper mandrel member is slid into said support.

3. A hair curler comprising a support, a lower mandrel member, an upper mandrel member slideable in said support, a narrowed slotted portion formed on one end of said upper mandrel and adapted to receive one leg of a hair pin therein and stop means for intercepting said leg of said hair pin as said upper mandrel member is slid into said support.

4. A hair curler according to claim 3 including spreading means for said hair pin integral with said upper mandrel member.

5. A hair curler comprising a support, a lower

mandrel member, an upper tubular mandrel member slideable in said support, means on said tubular mandrel member to receive and retain one leg of a hair pin within the hollow of one end of said tubular mandrel member, a wire connected to said support and extending into said tubular mandrel member whereby when said tubular mandrel member is slid rearwardly toward said support, said wire is caused to contact and to intercept said leg of said hair pin thereby forcing it off said tubular mandrel member.

6. A hair curler according to claim 5 including a narrow slotted section on said one end of said tubular mandrel member for maintaining a firm grip on said one leg of said hair pin.

7. The combination with a hair pin having two legs meeting in an arcuate closed end, of a hair curler comprising a support, a mandrel member slideable in said support, means on said mandrel member to receive and retain one leg of said hair pin, said means comprising a straight portion having a narrow slotted entrance whereby said one leg may be snugly received in said entrance until said arcuate end is reached, whereupon said arcuate end maintains a firm grip within said narrow entrance, and stop means on said support for intercepting said one leg of said hair pin when said mandrel member is slid into said support whereby said one leg of said hair pin is ejected from said mandrel member.

8. A hair curler according to claim 7 wherein said mandrel member is tubular and said stop means comprises a stationary wire connected to said support and partly located within the hollow of said tubular mandrel member so as to block the path of said one leg of said hair pin as it accompanies said mandrel member while being slid into said support.

9. A hair curler comprising a housing, a wire secured at one end thereof to said housing and extending the length thereof, a lower mandrel member, an upper, hollow mandrel member slideable into said housing thereby telescoping said wire, a hand-hold member connected to said upper mandrel member for sliding it, means on said upper mandrel for supporting a hair pin thereon by receiving and retaining a leg of said hair pin within said hollow of said upper mandrel whereby when said upper mandrel member is being completely slid into said housing, the end of said wire intercepts said leg of said hair pin and prevents it from entering said housing together with said upper mandrel member.

10. A hair curler according to claim 9 wherein the hair pin retaining end of said upper mandrel member has a narrow slotted section and the free end of said guide wire fits into said narrow slotted section to intercept said leg of said hair pin.

11. A hair curler comprising a housing, a wire connected at one end thereof to said housing, a tubular mandrel member slideable in said housing so as to telescope said wire and means to receive and retain one leg of a hair pin within the hollow of said tubular mandrel member whereby the sliding of said tubular mandrel member into said housing causes said wire to intercept said leg of said hair pin, preventing it from entering said housing together with said mandrel member and causing its ejection therefrom.

VICTOR M. NEWMAN.
